UNITED STATES PATENT OFFICE

MAX ROSENKRANZ, OF LIBRARY, AND SAMUEL WEBB, OF PITTSBURGH, PENNSYLVANIA, ASSIGNORS TO NATIONAL TUBE COMPANY, A CORPORATION OF NEW JERSEY

PIPE THREADING MACHINE

Application filed September 11, 1930. Serial No. 481,260.

This invention relates to pipe threading machines and it is among the objects thereof to provide mechanism for automatically opening the threading dies when a thread of 5 predetermined length has been cut and to automatically close the same when the carriage is returned to starting position.

Another object of this invention is to provide mechanism of the above designated character which shall provide for positive and accurate adjustment of the threading dies to maintain accuracy of the thread being cut.

Another object of the invention is the provision of die opening and closing mechanism 15 in which the force acting upon the die holders to close the dies is utilized to hold the dies against a stop to maintain the proper size of thread.

These and other objects will become more 20 apparent from a consideration of the accompanying drawings in which like characters designate like parts and in which:

Figure 1 is a side elevational view, partly 25 in section, of the die operating mechanism, showing a portion of the pipe threading machine bed on which it is mounted.

Figure 2 is a top plan view of the structure shown in Figure 1.

Figure 3 is a vertical cross-sectional view 30 through the dies and their cam operating mechanism.

Figure 4 is a front elevational view thereof.

With reference to the several figures of the drawing, the structure therein illustrated 35 comprises a machine bed 1 on which is mounted a carriage generally designated at 2 which consists of a pair of die holders 3 pivotally mounted at 4, and constituting a pair of winged members in which the thread cutting dies 5 are secured. The top of the die holders are provided with lugs 6 which cooperate with cam slots 7 of a cam plate 8 shown in dotted lines in Figure 2, the cam being adapted 40 for sliding movement in a horizontal plane and being actuated by a piston rod 9 having a piston head 10 operatively disposed in an air cylinder 11.

The movement of the cam plate 8 is controlled 50 by a valve 12 that is supported on the valve bracket 13 which is rigidly secured to

the carriage 2. The valve body 12 is provided with ports 13, 14, 15, 16 and 17 which cooperate with a valve plunger 18 to direct air pressure to the operating cylinder 11 through ports 19 and 20.

The plunger 18 is provided with a head having a shoulder 21 for engagement by a latch 22 that is mounted on a shaft 23, the latter being operated through a trigger 24 that is adapted to be actuated by a reamer plug 25 to release the latch 22. The reamer plug is slidably mounted in the carriage 2 and is held against rotation by a key 25a received in a key way 25b formed in the reamer. The latch and trigger parts are held in their normal position by a spring 26 acting upon a shaft 27 but are displaceable through the movement of the reamer 25. The latch 22 may be released by a hand lever 28 when it is desired to manually control the operation of 70 the cam plate.

The valve plunger 18 is provided with a bottom contact 30 which is adapted for engagement with a valve lifter 31 that is pivotally mounted at 32 to a bracket 33 on the machine bed 1 and the valve lifter 31 is operated by the valve bracket 13 which has a contact or engaging portion 34 that lifts the element 31 to raise the valve plunger 18 when the carriage 2 is returned to its normal position. The movement of the carriage 2 is controlled through suitable operating linkage, part of which is shown at 35 and which functions to move the carriage back and forth on the bed 1 of the machine. An adjustable stop 36 is provided and is fastened to the end of the machine by a bracket 37 to determine the limit of movement of the carriage 2.

One of the features of the invention is the provision of a combined stop and die adjusting device which comprises a wedge retainer 40 which is bolted to a die shoe 41, one of the bolts being shown at 41'. A stop or wedge 42 is adapted to move backward and forward in the wedge retainer 40 and is adjusted therein 45 by an adjusting nut 43 which can be locked in adjusted position by a lock nut 44.

The wedge 42 is designed to engage the die holders when the dies are in their closed position, the wedge acting as a stop block against 100

which the dies are forced. By means of the adjusting nut, the wedge 42 may be set to spread or contract the dies thereby providing for adjustment of the thread to be cut on the 5 pipe.

- The operation of the die closing and opening mechanism is briefly as follows: With the carriage 2 in position shown in Figure 1, resting against the stop 36, the valve lifter 31 10 is in engagement with the contact element 34 of the valve bracket 13, and the plunger 18 is in its raised position with the latch 22 in engagement with the shoulder 21 of the plunger. In this position, fluid pressure is 15 conducted through the port 13 around plunger 18 and out at the port 15 which communicates with the port 20 of the operating cylinder 11 at the side where the fluid pressure will act upon the piston 10 to move it towards 20 the back end of the carriage. Movement of the piston 10 will actuate the cam plate 8, causing it to move rearwardly and the cam slots, by virtue of their angularity, will contract the lugs 6 of the winged die holders, 25 causing the die holders to close in engagement with the wedge 42. The carriage is then advanced to engage the end of the pipe and the dies are fed automatically or by hand to form a thread on the pipe. When a thread of pre- 30 determined length has been cut, the reamer 25 manipulates the trigger 24 whereby the latch 22 is released and the plunger 18 which is normally biased in a downward direction by a spring 18a, moves downwardly, thereby 35 cutting off the source of fluid pressure passing to cylinder 11 through the port 13 and causing the cylinder 11 to exhaust through the port 20, port 15 and the port 17. Simultaneously therewith, air pressure is directed 40 from port 13 through port 14 to the back part of the cylinder 11 entering the latter through port 19 and causing the piston 10 to advance, thereby moving the cam plate in a direction to spread lugs 6 to open the die holders by virtue of the shape of the cam slots 7. 45
- The carriage is then returned to rest against the stop 36 and as the contact portion of the valve bracket 13 engages the valve lifter 31, the plunger 18 is again restored to its upper- 50 most position in which it is held by the latch 22. In this position air pressure is again communicated to the rear portion of the air cylinder 11 and the piston rod 9 is advanced to slide the cam plate 8 in a direction to contract 55 or close the die holders until they abut against the wedge 42 which is the closed or cutting position of the dies.
- The die holders may be operated by moving the hand lever 28 to release the latch 22 when 60 desired.
- By means of the die opening and closing mechanism herein described, the movement of the cam plate in a direction to hold the dies firmly against the wedge 42 and holder 47 65 produces greater accuracy of the dies in operation and by means of the adjusting of the

wedge element 42, the dies may be spaced to produce very accurate threads.

Although one embodiment of the invention has been herein illustrated and described, it will be obvious to those skilled in the art that 70 various modifications may be made in the details of construction without departing from the principles herein set forth.

We claim:

1. A thread cutting mechanism comprising 75 a movable carriage, a pair of die holders pivotally mounted thereon, a reaming plug carried by said carriage and slidably relative thereto, said plug being adapted to be engaged by the pipe to ream the end thereof, a lug on each of said die holders, a horizontal cam plate having cam slots therein converging outwardly and rearwardly from said die-holders, said lugs on said die holders being mounted in said slots, a fluid pressure actuating mechanism for said cam plate comprising 80 a piston, a valve controlling the pressure on both sides of said piston, a latch for holding said valve in position to close the dies, means operable by the movement of said carriage in a forward direction for moving said latch into holding position, said reamer plug being adapted to be moved rearwardly relative to said carriage when the pipe being threaded engages said plug, and means adapted 85 to be engaged and operated by said plug as it moves rearwardly for releasing said latch to permit said valve to operate and open said dies.

2. A thread cutting mechanism comprising 90 a movable carriage, a die shoe mounted on said carriage, a pair of die holders pivotally mounted on said die shoe, means for moving said die holders about their pivots to open and closed positions, a wedge retainer carried by said die shoe, a stop wedge mounted in said retainer and movable back and forth between the free ends of said die holders to limit the movement of said die holders towards each other, a threaded stem on said wedge, a nut threaded on said stem and carried by said wedge retainer for adjusting said wedge, and means for locking said wedge in its adjusted position.

In testimony whereof, we have hereunto 100 set our hands.

MAX ROSENKRANZ.
SAMUEL WEBB.
